UNITED STATES PATENT OFFICE

LOUIS MARTIN, OF ANACORTES, WASHINGTON

HAT-BLOCKING MACHINE

Application filed June 6, 1928. Serial No. 283,861.

My invention relates to an improvement in hat blocking machines of the general type shown in the patent to N. A. Sorenson, No. 1,598,028. This invention is particularly directed to the means for controlling the positioning of the shims.

Such a machine involves the employment of a rotatable and segmental head block, the segments being separable to permit the insertion between them of shims of selected sizes, whereby the head size of the block may be changed. Here, as in the Sorenson patent, these shims are arranged in sets, one corresponding to each gap between segments, and the complete set is rotatable with the head block. Means are provided which I shall term an "actuator", which, while it is rotatable with the head block, is fixed with relation to the shifting movement of the set of shims, so that it will engage at will any one of the shims in its set, to move the selected shim into position between the separated segments of the head block. Ordinarily, such an actuator and the shim are toothed, and the teeth, because of the peculiarity of conformation of the head block, and because of the difference in size and weight of the several shims, may not be kept in exact alignment if the shims are not guided or supported in some manner, hence it is necessary to provide some means for bringing these teeth or like engaging means, on the various shims, into exact position for engagement with the corresponding teeth, or like members, of the actuator, when in position to be engaged therewith, so that the actuator may move the shims into position between the segments.

My principal object, then, is to provide means for supporting, guiding, and engaging the shims, so as to bring them into proper position with respect to their actuator when about to be engaged therewith.

Generally speaking, then, it is my object to provide means for controlling the position of the shims, in association with such a rotatable head block.

It will be understood that the head block is in general elliptical, and such head blocks are normally made in four segments, separable along the major and minor axes of such an

ellipse. It will be understood that the shims which are movable into position between the segments, must travel different distances; that is to say, those which fit into the minor axis would have a somewhat greater distance to travel, if moved from the position they would naturally assume under the influence of gravity, than the shims which move into the major axis. Consequently, it is an object to provide means whereby the several shims, those which are intended to fit into the major and those which are intended to fit into the minor axis, will, by starting at different positions, reach their ultimate positions between the segments at the same time and with the same movement of the actuating means.

Among other objects, it is my object to provide a simple and convenient means for controlling the movement of shims employed, and especially the point from which their movement is started, in association with such a machine as that in the Sorenson patent referred to above, and all made with standard gear teeth.

My invention comprises the novel parts and the novel combination and arrangement thereof, such as is shown in the accompanying drawings, described in the specification, and as will be more particularly defined by the claims which terminate the same.

In the accompanying drawings I have shown my invention in a form which is now preferred by me.

Figure 1 is a general view of a typical machine embodying my improvement.

Figure 2 is an elevation, with parts broken away, illustrating the head block, the shims, and the shim rest means.

Figure 3 is an axial section through the head block and the shim supporting means.

Figure 4 is a section substantially on the line 4—4 of Figure 3, parts above this line being omitted.

The machine comprises a head block, generally designated by the numeral 1, and divided into segments 10, which are separable along planes of separation which coincide with planes through the major and minor axes of the ellipse formed by the outline of the head block 1. The outline of the block

is indicated by the dot and dash line H of Figure 4. This head block is suitably supported for rotation and for separation, as by guide sleeves 11, integral with the segments 5 10 and slidable upon radial pins 12, carried by a collar 13, fixed upon a rotatable support such as the shaft 2. Any suitable provisions may be made for separating the segments, and as shown herein the means disclosed in 10 the Sorenson patent is employed, this consisting of links 14 connecting the sleeve 11 with a collar 15 which is caused to slide axially of the shaft 2 by any suitable means (not shown).

15 The shims 3 are arranged in sets, one set corresponding to each of the gaps between segments. They must rotate with the head block, and to that end are supported upon guide rods 30, which are positioned at right 20 angles to the planes of separation between the various segments. The sets of shims are shiftable, each longitudinally of its guide rod 30, to bring any selected shim in the set into position for movement into the corresponding gaps between segments. To support the guide rod 30 and the shims 3, any suitable means may be employed, and I have 25 illustrated the spider 31, secured upon the shaft 2.

30 For shifting the sets of shims all the shims of each set may be suitably mounted upon a sleeve 32, which sleeve is directly slidable upon its guide rod 30, and the movement of this sleeve and the set of shims is controlled 35 by some suitable means, such as the ratchet lever 33, having a dog 34 engageable in the notches 35 of the rod 30, to exactly position a selected shim. The several sets of shims may be connected for simultaneous movement by 40 some such means as the spider 36, rotatable upon the shaft 2, and connected to each of the sleeves 32 (see Figure 4), hence but one ratchet lever 33 is necessary. All of this construction is old, as shown in the Sorenson 45 patent, and forms no part of my invention.

50 Similarly, the means for actuating the shims is similar to that shown in the Sorenson patent, and comprises a toothed actuator 4 for each set of shims, these several actuators 55 being pivotally supported at 40 upon a collar 41, fixed upon the shaft 2, and the several actuators being connected for simultaneous actuation by a spider 42, pivoted at 43 to the individual actuators, which spider 42 is rotatable with but movable axially of the shaft 2 by any suitable means (not shown). Each 60 of these actuators 4, therefore, is rotatable with the head block, but is fixed with respect to the shifting movement of its set of shims, so that in shifting the shims they are moved 65 past the actuator which corresponds thereto, each shim in the set coming in turn into engagement with the actuator. The shims are shown as provided with teeth 37, which mesh 70 with the teeth of the corresponding actuator

4. These teeth are standard gear teeth, and if the shims in a set do not all hang down at the same angle these teeth will not be in alignment.

70 It will be noted that the shims 3 are of a peculiar hooklike shape to correspond to the contour of the head block into which they fit. Some of these are of considerably greater width, or thickness, than others, and consequently of greater weight, and owing to their peculiar shape these shims would, if permitted to hang free, depend in such position that the teeth 37 of the various shims of a set would not be in alignment. This difficulty has been met with in the Sorenson machine, 80 wherein it was found necessary to use teeth which permitted considerable lost motion, and which, therefore, did not bring the several segments into final position properly nor uniformly. In order to cause the teeth 37, as they approach the actuator 4, to come into position for exact alignment and meshing therewith, I have provided a shim rest means, which, as shown here, consists of a ring 5 supported upon the shaft 2 and rotatable therewith. Inasmuch as there are four gaps between segments and four actuators 4, each corresponding to its respective gap, there need be but four points on the ring 5 which need to be exactly positioned, but for a purpose which will appear hereafter, I prefer to make the ring 5 elliptical, and to position it so that its major axis is at right angles to the major axis of the head block, as indicated in Figure 4.

90 It is essential that the shims in the several sets be so moved as to bring their tips to the center of the head block at precisely the same time, so that no provision need to be made for lost movement in the actuating means for any shim. Considering the tips of the shims which fit within the minor axis of the head block; it will be seen that if these shims were permitted to hang down their tips would not be the same distance from the axis of the shaft 2 as the tips of those shims which are to fill the gap in the major axis of the head block, for the reason that the bent portions of the latter are somewhat longer than the bent portions of the former, and somewhat heavier, and hence would gravitate to a different position of rest. If all were to be moved simultaneously from such position as they would naturally assume, the tips of the shorter shims, those which fill the gaps in the minor axis of the head block, would arrive first, having the shorter actual distance to travel. To compensate for this, then, and to shorten the distance which the longer shims, those which fill the minor axis, must travel, the shim rest 5 is made elliptical and so placed that its major axis is at right angles to the major axis of the head block. This gives the shims which fill the minor axis of the head block a little lead on the other 100 110 120 130 140 150 160 170 180 190 200 210 220 230 240 250 260 270 280 290 300 310 320 330 340 350 360 370 380 390 400 410 420 430 440 450 460 470 480 490 500 510 520 530 540 550 560 570 580 590 600 610 620 630 640 650 660 670 680 690 700 710 720 730 740 750 760 770 780 790 800 810 820 830 840 850 860 870 880 890 900 910 920 930 940 950 960 970 980 990 1000 1010 1020 1030 1040 1050 1060 1070 1080 1090 1100 1110 1120 1130 1140 1150 1160 1170 1180 1190 1200 1210 1220 1230 1240 1250

shims, sufficient to make their tips all arrive at the axis of the head block at the same time, with a given movement of the actuator 4.

Thus, the shim rest 5 accomplishes two ends. It keeps the teeth 37 in alignment with the teeth of the actuator 4, or at least brings the teeth 37 into position to mesh exactly with those of the actuator, and in addition, the shim rest 5 causes the shims to be positioned automatically in such fashion that upon simultaneous movement of all the actuators through a given distance, the shims themselves will move through a given distance and arrive at their ultimate position all at the same time.

What I claim as my invention is:

1. In a hat blocking machine, in combination, a segmental head block, means for separating the segments, an actuator member corresponding to and fixed relative to each gap between segments, means for moving all of said actuators simultaneously, a plurality of sets of size-changing shims, one for each gap, and shiftable past each gap and the corresponding actuator, to engage a selected and corresponding shim in each set with its actuator, to be moved thereby into position between the separated segments, and means for positively positioning each shim in each set, as it approaches its actuator, for exact engagement therewith.

2. In a hat blocking machine, in combination, a rotatable segmental head block, means for separating the segments, a plurality of actuators, one corresponding to and fixed relative to each gap between segments, and all rotatable with the head block, means for moving all of said actuators simultaneously, a plurality of sets of size-changing shims rotatable with the head block, one set for each gap, and shiftable past its gap and the corresponding actuator, to engage the several actuators each with a selected and corresponding shim in each set, to move the selected shims into operative position, and means engageable with said shims, and spaced from its support, to position each shim in each set, as it approaches its actuator, into position for exact engagement therewith.

3. In a hat blocking machine, in combination, a rotatable head block having a major and a minor axis, and formed of segments separable along such axes, means for separating the segments, a plurality of actuators, one corresponding to and fixed relative to each gap between segments, and all rotatable with the head block, a plurality of sets of swinging, pivotally mounted, size-changing shims rotatable with the head block, one set for each gap, and shiftable past its gap and the corresponding actuator, to engage the several actuators each with a selected and corresponding shim in each set, means for moving all the actuators simultaneously to move the selected shims into operative position, and

means rotatable with the head block, and continuously engaged by said shims, to position each shim in each set, as it approaches its actuator, into position such that the swinging ends of those shims which will occupy the major axis are equidistant from the center of the block, measured through their path of swing, with the swinging ends of those shims which will occupy the minor axis.

4. In a hat blocking machine, in combination with a segmental head block, a plurality of toothed actuators, one for each gap between segments, a plurality of sets of size-changing shims, one set for each gap, each of said shims having teeth engageable with the corresponding actuator, means for shifting the sets of shims transversely of its actuator and gap, to bring any selected shim, in each set, into engagement with its actuator, and a shim rest ring engaging and guiding the several shims, as they are shifted while in inoperative position, to bring the teeth of the several individual shims of a set into exact alignment with the teeth of the corresponding actuator.

5. The combination of claim 4, the head block being elliptical and the shim rest ring being likewise elliptical, but with its major axis at right angles to the major axis of the head block.

6. In a hat blocking machine, in combination, a rotative shaft, a segmental head block supported thereon and rotatable therewith, means for separating the segments, a shim support rotatable with the shaft and head block, a plurality of sets of shims, one for each gap between segments, supported on said shim support, each set of shims comprising a plurality of shims of different sizes, means for shifting the sets of shims relative to the corresponding gaps between segments, to bring a selected shim in each set opposite its gap, an actuator for each set of shims rotatable with the shaft and block, but fixed relative to the movement of the shims in shifting, and positioned to engage a selected shim to move it into the gap between segments, and a shim rest rotatable with the shaft and block, and engaging the shims to position each shim, as it approaches its actuator, for exact engagement thereby.

7. In a hat blocking machine, in combination, a rotative shaft, a segmental head block supported thereon and rotatable therewith, means for separating the segments, a shim supporting guide rod extending normal to each plane of separation of the segments, and rotatable therewith, a set of shims of different sizes slidable along each of said guide rods, to bring a selected shim in each set in position to enter its corresponding gap between segments, an actuator for each set of shims rotatable with the shaft and block, but fixed relative to the movement of the shims in shifting, and positioned to engage a selected shim to move it into the gap between segments,

and a shim rest rotatable with the shaft and block, and engaging the shims to position each shim, as it approaches its actuator, for exact engagement therewith.

8. In a hat blocking machine, in combination, a rotative shaft, a segmental head block supported thereon and rotatable therewith, means for separating the segments, a shim supporting guide rod extending normal to each plane of separation of the segments, and rotatable therewith, a set of toothed shims of different sizes shiftable upon each of said shim supports, to bring a selected shim in each set into position to enter its corresponding gap between segments, a plurality of toothed actuators, each adapted to mesh with any selected shim in its corresponding set, said actuators being rotatable with the shaft and block, but fixed relative to the movement of the shims in shifting, and means engageable with the shims to position them, as each approaches its actuator in shifting, for exact meshing of their teeth with the actuator teeth.

9. In a hat blocking machine, in combination with a head block having a major and a minor axis, and formed of segments separable along such axes, a plurality of actuators, one for each gap between segments, a plurality of sets of pivotally mounted size-changing shims, one set for each gap, each of said shims having teeth engageable with the corresponding actuator, means for shifting each set of shims transversely of its actuator and gap, to bring any selected shim, in each set, into engagement with its actuator, means for swinging the several selected shims simultaneously into the gaps between segments of the block, and means for adjusting the starting point of the ends of the various shims in their several paths of movement, to complete such movements simultaneously into operative position in their respective gaps.

Signed at Anacortes, Skagit County, State of Washington, this 26th day of May, 1928.

LOUIS MARTIN.
